UNITED STATES PATENT OFFICE.

KATHRYN L. VALENTINE AND GEORGE RAMSEY, OF JERSEY CITY, NEW JERSEY.

OVERSHOE.

Application filed April 21, 1927. Serial No. 185,389.

Our invention relates to overshoes.

Our invention includes means to make overshoes readily attachable to the foot. In place of the troublesome snaps, buckles, slide 5 fasteners or other devices at present used to attach foot coverings to feet, we so construct the top portion of our foot covering that it may readily expand, and insert elastic metallic means in the periphery thereof to cause 10 contraction thereof and yieldable to permit expansion thereof for insertion of the foot, the elastic metallic means preferably being limited in its stretching movement to less than its elastic movement by the inelastic extended 15 top. While we are aware that others have attempted to make portions of an overshoe elastic, the present day practice of the manufacturing of overshoes normally includes a vulcanizing process after the parts of the 20 overshoe have been put together and the heat employed in the vulcanizing process normally tends to destroy the elasticity of the elastic means formerly employed. We have discovered that by using an expandable metallic means such as a concealed metallic 25 spring, the overshoe may be heated up to the temperature necessary in vulcanizing without impairing the resiliency of the elastic metallic means. 30 This invention is an improvement on our application for patent for overshoe Serial No. 175,854, filed Mar. 16, 1927. Instead of the specific embodiment of our invention shown therein, wherein the expandable means 35 completely encircles the foot or leg, in our present embodiment we preferably construct a portion of the periphery of the top portion of a non-expandable portion adapted to snugly fit the foot and the rest of the periphery thereof of an expandable portion of greater width than necessary to compactly 40 fit the foot, adapted to be crinkled when attached to the foot and retained in crinkled position compactly binding the top of the 45 foot by resilient metallic means connected to adjacent sides of said inelastic portion and extending across said expandable portion. In the preferred embodiment shown, we preferably employ a plurality of expandable metallic means extending horizontally 50 at spaced intervals across said expandable portion or portions. In our preferred embodiment, we also preferably conceal the elastic metallic means between the lining and the outer covering thereof. We preferably employ a spring which when in contracted posi-

tion will not bind the foot so as to impair circulation and we have found a coil spring, which due to its inherent construction performs this function, an ideal means to employ. We also preferably limit the stretching movement of the elastic metallic means to less than its elastic limit by the extended width of the expandable portion of the top or otherwise such as by a cord. 60

In our preferred embodiment we preferably make the expandable portions of our overshoe by inserting expandable V-shaped gussets in each side thereof and preferably provide a plurality of coil springs extending 65 horizontally at spaced intervals across said gussets. It is thus apparent that in order to insert the foot it is merely necessary to pull radially outwards on the top, permitting the top to expand to permit the foot to be inserted through the mouth and then to permit the elastic metallic means to contract to firmly retain the top to the foot and lower portion of the leg. In order to take off an overshoe equipped with our invention, it is 70 merely necessary to press down on the heel thereof with the other foot and the elastic metallic means will expand, permitting the foot to be withdrawn through the expanded mouth, an operation similar to that of the 75 present day practice of taking off a rubber. 80

These and such other objects of our invention as may hereinafter appear will be best understood from a description of embodiments thereof such as are shown in the accompanying drawings. 90

In the drawings, Fig. 1 is a perspective view of the preferred embodiment of our invention which has V-shaped expandable gussets inserted in the periphery of the top 95 at each side thereof with the top contracted in attached position on the leg of the wearer.

Fig. 2 is a perspective view similar to Fig. 1 with the top expanded for insertion or removal of the foot. 100

Fig. 3 is a detailed view of the top portion of an embodiment of our invention employing only one spring in each gusset.

Fig. 4 is a detailed view of the spiral spring we preferably employ. 105

Fig. 5 is a vertical sectional view taken along the line 5—5 of Fig. 3.

Fig. 6 is a perspective view of a modified form of our invention, wherein the expandable portion comprises the back portion of the 110 top of an overshoe.

Fig. 7 is a further modified view of our

invention, wherein the expandible portion comprises the front of the top portion of an overshoe.

In the drawings, wherein like characters of reference indicate like parts throughout, 10 generally indicates an overshoe constructed in accordance with our invention. We preferably construct our improved foot covering with the usual sole portion 11 and the usual 10 top portion 12 secured to said sole and adapted to cover the upper part of the foot. It is obvious, however, that the sole portion need not completely cover the sole as in a spat or legging. The top portion 12 terminates in a 15 mouth 13 for the leg in the upper end thereof. We preferably construct the top portion 12 of an inelastic portion 15 adapted to snugly and evenly fit the foot and an expandible portion of greater width than necessary for a 20 tight fit inserted in the periphery thereof. In the preferred embodiment shown in Figs. 1-5 the inelastic portion 15 comprises the rear portion 16 of the top and the separate front portion 14. In the embodiment shown in 25 Fig. 6 the non-expandible portion comprises the front portion 14 and the embodiment shown in Fig. 7 the non-expandible portion comprises the back portion 16. In the embodiment shown in Figs. 1 to 5 the expandible 30 portion 17 comprises the connecting portions or gussets 18 preferably V-shaped inserted at each side of said overshoe between said front and back portions adapted to be crinkled when closely attached to the inserted foot and leg. In the embodiment shown in Fig. 6 the expandible portion 17 comprises the back portion 16 and in the embodiment shown in Fig. 35 7 the expandible portion 17 comprises the front portion 14. In our preferred embodiment 40 the entire top functions in its opening and closing movement somewhat similar to a bellows.

It is thus apparent that after the top portion 12 is constructed as shown, it will be expandible and when in closed position on the foot will assume the position shown in Fig. 1 and when in open position for insertion or removal of the foot will assume the expanded position shown in Fig. 2. To normally retain the top 12 in closed position when attached to the foot and to firmly retain the overshoe to the foot, we preferably provide the expandible metallic means 20 in the periphery thereof having the ends 21 thereof 50 attached to the sides of said inelastic portion 15 adjacent the expandible portion 17 thereof and extending across the expandible portion 17. The tendency of the resilient metallic means 20 to contract causes said top 55 12 when closed to yieldingly retain the overshoe to the foot. As the metallic means 20 is elastic, however, it may readily expand to permit the top 12 to assume the position shown in Fig. 2 for insertion or removal of 60 the foot. Though any suitable type of elastic

metallic means may be employed, we preferably provide a type which is limited in its contracting movement and we have found coil springs particularly suitable for this purpose. We, therefore, as our preferred type 70 of elastic metallic means, employ the coil spring 20 as shown in Fig. 4, extending across said expandible portion 17 and having each end 21 thereof attached to adjacent portions of the inelastic portion 15. We also preferably so construct the width of the expandible portion 17 and select springs 20 of the desired resiliency so that the expandible portion 17 will limit the stretching movement of the springs 20 to less than their elastic limit, to 80 last a relatively long time in use and to firmly retain the overshoe to the foot. As stated, we preferably employ expandible metallic means so that the resiliency thereof will not be impaired in the heating necessary for vulcanizing the parts of the overshoe together. If desired, other means may be employed to prevent extension of the springs beyond their elastic limit, such as the cord 25 inserted within the spiral spring 20. Though, as shown in 85 Fig. 3, in a short type of overshoe, we may only employ one elastic metallic means extending across each expandible portion 17, in our preferred embodiment we preferably employ a plurality thereof extending horizontally at spaced intervals across said expandible portions 17, preferably from the top to the bottom of said top portion 12.

A top portion of an overshoe normally includes both the inner lining 28 and the outer covering 30 which in practice are cemented together by the cement 29 and as shown herein we preferably attach said resilient means between said outer covering 30 and inner lining 28 so as to be completely concealed from 100 view. In order that said springs 20 may freely expand and contract between said outer covering 30 and lining 28, we loosely enclose them in any suitable means such as the tubes 31 preferably constructed of tape inserted between said covering 30 and lining 28 and in practice having the outer surfaces thereof cemented thereto.

In practice the operation of the preceding paragraph may be accomplished as follows: 115 before the outer covering 30 and inner lining 28 are cut in pieces to the shoe dimensions they are suitably covered with a rubber cement suitable for vulcanizing by calendering a layer thereof thereon. When these are 120 made up into a shoe the shoe is formed so as to make these rubberized surfaces adjacent, viz: with the rubberized surface of the outer covering 30 being on the inside thereof and the rubberized surface of the inner covering 28 125 being on the outside thereof. The rubberized inserts are then secured to the inelastic front and rear portions of the shoe by vulcanization, this step forming a bond between the inserts and the remaining portions of the 130

overshoe. If desired, the tubular covering means 31 may be merely inserted between these two rubberized surfaces prior to vulcanization but we preferably either brush, paint or otherwise affix a layer of additional cement around the tubes 31 before insertion between the lining 28 and covering 30, so as to provide more cement to aid in binding the tubes 31 thereto. When the entire shoe has been subjected to the vulcanizing treatment the tubes 31 will be uniformly cemented to the inner lining 28 and the outer covering 30 by the cement 29 shown in Figure 5. As the springs 20 are inserted in the tubes 31 prior to their insertion between the outer covering 30 and inner lining 28 in the manufacture of the shoe, it is obvious that they will be loosely contained within the tubes 32 and free to expand or contract therein. As stated we prefer to employ the resilient metallic springs in order to provide an elastic means which will withstand the high heating treatment of the vulcanization.

It is apparent that we have provided a novel type of overshoe very easily attached to the foot and have eliminated the troublesome snaps, slide fasteners, buckles or other types of devices formerly employed to secure the overshoe thereto. To attach, it is merely necessary to pull out radially on the top portion 12, the elastic metallic members 20 readily expanding to their extreme position shown in Fig. 2 and the expansible portions 17 expanding to extended inelastic position when the foot may be readily inserted or withdrawn from the overshoe. After the foot is inserted, it is obvious that the springs 20 will contract to cause the entire top 12 to contract to firmly retain the overshoe to the foot, the expansible portions then assuming a crinkled position as shown in Fig. 1. To detach, it is merely necessary to put the toe of the opposite foot against the heel and push down on the heel thereof when the elastic members 20 will expand, permitting the top 12 to open up to expanded position to permit the overshoe to slide off the foot. If desired, however, in taking off the overshoe the top may be pulled radially outwards for expansion as is normally done in putting on the shoe.

Our invention is adapted for use in any type of overshoe such as galosh, legging, spat or otherwise, preferably one which is waterproof, and we therefore in the claims employ the word "overshoe" to mean any separate covering for the foot that would be worn over a shoe, pump, slipper or other normal type of foot covering, and when in this application we employ the words "attached to the foot, etc." we refer to the foot as being covered with a suitable inner foot covering such as a shoe.

It is understood that our invention is not limited to the specific embodiments shown and that various deviations may be made therefrom without departing from the spirit and scope of the appended claims.

We claim:

1. A vulcanized waterproof overshoe comprising an inelastic portion, an expansible upper portion, said upper portion comprising an outer covering and an inner lining cemented together, tubular means extending across said expansible portion of a width substantially equal to that of said expansible portion and cemented to the inner covering and outer lining thereof, and elastic metallic means loosely contained within said tubular means attached to said inelastic portion adjacent said expansible portion to retain said portion contracted and permit expansion thereof.

2. In an overshoe of the class described, an inelastic upper portion, an elastic section in said upper portion, said section comprising an inner insert, an outer insert and an intermediate layer of fabric between said inserts, said inserts being secured to said upper portion, and elastic metallic means interposed between said intermediate layer and one of said inserts and secured at its ends to said inelastic upper portion, the opposite side of said layer being vulcanized to the other of said inserts.

3. In an overshoe of the class described, an inelastic upper portion, an elastic section in said upper portion, said section comprising an inner insert and an outer insert, said inserts being secured to said inelastic portion, elastic metallic means interposed between said inserts and secured at its ends to said inelastic portion, and means associated with said metallic means and secured to said inelastic portion to limit the expansion of said elastic means to less than its elastic limit.

4. In an overshoe of the class described, an inelastic upper portion, an elastic section in said upper portion, said section comprising an inner insert and an outer insert, said inserts being secured to said inelastic portion, elastic metallic means having a normal length less than the expanded width of said section, said metallic means being interposed between said inserts and secured at its ends to said inelastic portion, and an inelastic cord contained within said elastic means to limit the expansion of said elastic means to less than its elastic limit.

In testimony whereof, we have signed our names to this specification this seventh and fifth day of April, 1927, respectively.

KATHRYN L. VALENTINE.
GEORGE RAMSEY.
